UNITED STATES PATENT OFFICE.

ALBERT VEITINGER, OF WURTEMBERG, GERMANY.

PROCESS OF PRODUCING TRANSPARENT WINDOWS IN PAPER, CARDBOARD, AND THE LIKE.

No Drawing. Application filed March 25, 1925. Serial No. 18,318, and in Germany April 10, 1924.

The usual method of producing transparent windows in paper, cardboard, or the like, consists in cutting out portions of the sheet, to make apertures of the size and shape of the windows required, and then cementing to the rim around each aperture a sheet of gelatine or other transparent material adapted for the purpose. These small sheets of gelatine or the like are first cut to 10 the proper size and shape out of a larger sheet. This method is inconvenient, largely for the reason that the gelatine sheets are liable to curl and it is not easy to do the work neatly, with a perfect joint around the 15 window aperture, and comparatively thick films must be used.

According to my invention the "glazing" of the windows is performed in the following way. A thin layer of gelatine or other 20 colloidal matter, which will harden to form a solid but transparent film, is spread upon a slab, say a sheet of glass, and while it is still soft or viscous the sheet of paper or the like, in which the apertures have been

made, is spread on it and pressed, rubbed or 25 brushed, without damaging the surface of the colloidal substance exposed by the apertures, over which a suitable cover may be placed. When the colloidal substance has become sufficiently dry or hard, it is detached from the slab, together with the sheet of paper or the like which it covers. This leaves all the windows "glazed" by 30 portions of a film which covers the whole sheet. 35

What I claim as my invention and desire to secure by Letters Patent of the United States is:—

The process of covering apertures in a sheet with a transparent film, consisting in 40 spreading the sheet on a film of viscous material adapted to adhere thereto and to harden to a solid transparent film, the area of the film being at least equal to the area of the sheet. 45

In witness whereof I have signed this specification.

ALBERT VEITINGER.
